Patented Aug. 23, 1921.

UNITED STATES PATENT OFFICE.

GEOERGE BUTTRESS, OF LOS ANGELES, CALIFORNIA.

EXPANDING PULLEY.

1,388,797.

Specification of Letters Patent. Patented Aug. 23, 1921.

Application filed November 19, 1919, Serial No. 339,187. Renewed January 24, 1921. Serial No. 439,690.

To all whom it may concern:

Be it known that I, GEORGE BUTTRESS, a citizen of the United States, residing at Los Angeles, county of Los Angeles, and State 5 of California, have invented a certain new and useful Improvement in Expanding Pulleys, of which the following is a specification.

My invention relates to an improvement 10 in pulleys, and has particular reference to pulleys of the expanding type for varying the velocity ratio by expansion and contraction of the periphery, one of the objects of this invention being to provide a simple, 15 light and efficient unit, of economical construction, in which, during all conditions of expansion and contraction, a smooth and continuous peripheral face may be had whereby to afford a continuous friction hold 20 for the belt or other driving or driven medium.

Other objects will appear from the subjoined specification in connection with the accompanying drawing, which illustrates a 25 preferred form of embodiment of the invention, and in which,

Figure 1 is a vertical section, taken on line 1—1, Fig. 2.

Fig. 2 is a side view, partly in section 30 showing a fragment of one of the plates for holding rigid the radial arm of the pulley.

Fig. 3 is an enlarged front view of one 35 of the arcuate sections showing the anchoring thereto of the facing strip or ribbon and the continuation of the strip under the fastened or anchored end thereof.

Fig. 4 is a horizontal sectional view taken 40 on line 4—4, Fig. 2, of one of the arcuate sections composing the pulley, and

Fig. 5 is a plan view showing means for 45 expanding and contracting the pulley, and means tending to convert the pulley to its largest diameter or size.

The invention comprises a series of 50 flanged arcuate sections or segments 1, each provided with ears or lugs 2, for pivotally connecting the ends 3' of radial arms 3, the opposite ends of which are pivotally attached to ears 5, on disks 6, secured to drums 55 7 that are keyed to and slidable on a shaft 8.

With the exception of one, each of the flanges 9, of the arcuate members or sections 1, is formed with an inwardly extended portion 10, rotund on the underside, and spaced 55 from the surface of the arcuate section to form a groove 11, for the accommodation

of a circumferential band 12, preferably of resilient material, which entirely encircles the arcuate sections.

One of the arcuate sections, to wit, the section 1^a is not flanged, and onto the outside edges thereof are riveted or otherwise fixed, the ears 11', formed on the band 12 and bent at right angles, in such manner that the plane of the band, for a distance 60 equal to the thickness thereof, is held spaced from the surface of the arcuate section 1^a, in order to afford space for the returning convolution 12^a of the band 12, which convolution continues for a distance desired 65 and governable by the extent of expansion of the pulley, and terminates within the area of the associated arcuate sections. The movement of the drums 7 on the shaft 8, is effected by any suitable mechanism, as 70 75 toggle joints 14, the toggles 15 of which are pivotally connected to straps 16 of drums 17, pinned on the shaft, and levers 18 being pivotally attached to the junction of the joints.

The levers 18, in turn may be pivotally connected with an operating bar 19, by 80 which the contraction or expansion of the arcuate section through the medium of the radial arms 3 may be effected. During the 85 change in the periphery of the arcuate sections, the convolution of the band 12, is extended or diminished, and always bridges the space between the arcuate sections, as it is moved by the section 1^a, to which it is 90 permanently attached.

Obviously, when two such pulleys are 95 connected by a belt, the expansion of one and the contraction of the other, may be effected simultaneously by the operation of the bar 19, which, after the adjustment is made, may be held rigid by any means.

In order to offset the strain on the arms 3, during the operation of varying the pulley periphery, two disks 20 and 21 may be 100 provided. These disks or circular plates are securely held together by any means, as bolts 24, and are provided with slots 22 and 23, into which the ends of the radial arms 3 extend and in which they may move 105 during the expansive and contractive movements of the arcuate sections.

In order to make easy the expansion of the arcuate members or sections during rotation of the same, the disks 6 of the drums 110 7 may be interconnected by a means tending to draw the drums toward each other,

and such means may comprise springs 25, which, as is obvious, reduce the power required for expanding the pulley and likewise resist the normal tendency of the pulley to contract by reason of the pressure of the belt.

Each of the arcuate sections 1 is preferably provided with an antifriction means for the band 12 during the movement thereof, and such antifriction means may be rollers 26, or any other means suitable for the purpose.

What I claim, is:—

1. A pulley comprising in combination a series of arcuate sections constructed to grip a band against radial movement in respect thereto and to permit the band to slide circumferentially, a series of drums, radial arms connecting said drums and sections, a convolution of a resilient band fastened at one end to one of said sections and encircling the others of said sections so as to slide circumferentially in the latter, said band being free at the other end and continuing under said sections.

2. A pulley comprising in combination with a shaft, a pair of carriers secured to said shaft, a series of arcuate sections mounted to radially slide in said carriers, said sections being constructed to grip a band against radial movement with respect thereto and to permit the band to slide circumferentially, a series of drums, radial arms connecting said drums and sections, a convolution of a resilient band fastened at

one end to one of said sections and encircling the others of said sections so as to slide circumferentially in the latter, said band being free at the other end and continuing under said sections.

3. A pulley comprising in combination with a shaft, carrier disks secured to said shaft and having radial guide ways, a series of arcuate sections slidably mounted in said guide ways, said sections being constructed to grip a band against radial movement with respect thereto and to permit the band to slide circumferentially, a series of drums, radial arms connecting said drums and sections, a convolution of a resilient band fastened at one end to one of said sections and encircling the others of said sections so as to slide circumferentially in the latter, said band being free at the other end and continuing under said sections.

4. A pulley comprising in combination a series of arcuate sections constructed to grip a band against radial movement with respect thereto and to permit the band to slide circumferentially, a series of drums, radial arms connecting said drums and sections, a convolution of a resilient band fastened at one end to one of said sections and encircling the others of said sections so as to slide circumferentially in the latter, said band being free at the other end and continuing under said sections, and means normally to hold said drums under tension.

In testimony whereof I have set my hand.
GEORGE BUTTRESS.
